PERMANENT WAVING

Carl G. Gross, Mount Vernon, N. Y., assignor, by
mesne assignments, to American Machine and
Metals, Inc., New York, N. Y., a corporation of
Delaware

Application November 23, 1932, Serial No. 643,993

5 Claims. (Cl. 132—36)

The present invention relates to apparatus for permanent waving and more particularly to a novel and improved heater for permanent waving.

5 Objects and advantages of the invention will be set forth in part hereinafter and in part will be obvious herefrom, or may be learned by practice with the invention, the same being realized and attained by means of the instrumentalities 10 and combinations pointed out in the appended claims.

The invention consists in the novel parts, construction, arrangements, combinations and improvements herein shown and described.

15 The accompanying drawing, referred to herein and constituting a part hereof, illustrates one embodiment of the invention, and together with the description, serves to explain the principles of the invention.

20 Of the drawing:

Figure 1 is a fragmentary side elevation of one embodiment of the present invention and showing different types of heaters which may be used therewith;

25 Figure 2 is a detailed side elevation of a heater unit in accordance with the present invention; and

Figure 3 is a longitudinal section of a cord gripping and supporting device in accordance 30 with the present invention.

The present invention has for its object the provision of a new and improved heater mechanism for permanent waving in which the heating units may be readily and individually moved, and replaced in whole or in part by other heating units of the same or a different kind. A further object is the provision of an improved heating unit which is bodily removable from a supporting member usually positioned above the 40 customer's head. Still another object is the provision of an improved gripping and supporting member for the heater cords which may be bodily removed from or attached to a main supporting member, and which permits the length 45 of cord between the supporting member and the customer's head to be varied.

Referring now in detail to the illustrative embodiment of the invention as shown in the accompanying drawing, a supporting and electricity 50 distributing member is provided which is generally positioned immediately above the customer's head and is supported upon a standard 10, or may depend from the ceiling. This supporting and electricity distributing member, as 55 embodied, comprises an annular member or drum

11 provided with a plurality of pairs of female connectors 12 set in the drum 11 in a pair of rows, one superposed above the other, and preferably with a row of grounding contacts 13 positioned between the connectors 12. Drum 11 is 60 rigidly secured to the standard 10 in any desired manner.

Surrounding the annular member 11, and preferably positioned very slightly above it, is a relatively large and narrow circular band 14, also 65 supported from standard 10 by means of radial spokes (not shown). Band 14 is provided with a plurality of slots 15 for receiving and holding the cord gripping and supporting members, later to be described, and the number of such slots 70 15 is preferably at least as great as the maximum number of heaters to be employed at any one time.

The heating units in accordance with the present invention are bodily detachable from 75 their support as a unit and comprise heaters 16, which may be of any desired type, as are used in giving a flat wave, and as shown in Figure 2, or those of tubular form, as at 17 to be used in waving a helically wound tress. As embodied, a 80 pair of such heaters are connected in series with the terminals 18 of the male portion of a separable connector 19 by means of flexible conductors 20, the terminals 18 being adapted to contact with a pair of terminals 12 on the annular member 11.

The heating units preferably include means for frictionally gripping and supporting the heaters 16 or 17 and their flexible conductors 20 upon the circular ring 14, and for this purpose 90 each of the conductors is provided with a cord gripping device which is bodily detachable from the ring 14. As embodied, this cord gripping device comprises a relatively small body 22, preferably of insulating material, and formed 95 with a pair of spaced apart axially aligned apertures 23 through which the heater cord 20 may be threaded. Positioned between said apertures 23, and capable of axial alignment therewith, is an annulus 24 surrounding the heater cord 20, 100 and provided with a relatively smooth inner face.

Means are provided for resiliently urging annulus 24 out of alignment with apertures 23, and into the position shown by Figure 3, so that it will firmly grip and securely hold the heater 105 cord 20 at any point, while permitting the relatively easy movement of the cord back and forth through the device. For this purpose, a pin 25 is attached to annulus 24 and extends radially therefrom, and is received within a socket in 110

pin 26 which is securely fastened in the body 22. A small spring 27 is compressed between the end of pin 25 and the bottom of the socket in pin 26, and serves to urge annulus 24 into frictional and gripping contact with the cord 20.

For attaching the cord gripping device to the supporting ring 14, pin 26 is provided with a narrow T-head 28 at its outer end, which corresponds in size and shape to the slots 15, and forms a bayonet connection therewith. The heads 28 may be passed through the slots 15, and by turning the gripping device 90 degrees to the position shown in Figure 1, the heater cords are supported on the supporting ring 14, but may be readily removed therefrom by rotating the gripping device 90 degrees and pulling it away from the ring.

In operation, the required number of heaters are connected to the electricity distributing member 11 by means of separable connectors 19, and the cord gripping and supporting members 22 are properly positioned and supported on the ring 14, with the heaters hanging downwardly therefrom. After the heaters 16 or 17 have been properly positioned on the customer's head, the slack in the heater cord 20 between the customer's head and the cord gripping and supporting members 22 may be taken up by pulling the cord 20 upwardly through the cord gripping devices 22, thereby relieving the weight of the heaters from the customer's head and supporting them from the ring 14.

In case a particular heater becomes damaged, or it is otherwise desirable to replace it, it is only necessary to remove the separable connector 19 from the distributing member 11 and thereafter to detach the two supporting and gripping devices 22, thereby freeing the particular heating unit and permitting its bodily removal. In the same way it is possible to remove all of the heaters and to replace them by heaters of a different type when it is desired to give a different kind of a permanent wave. An operator need be provided with only a single machine and different sets of heaters in order to give different kinds of waves, thereby reducing the cost of the equipment and effecting a great economy in the space required for the apparatus. The present invention also permits replacement of a defective heater instantly and without the use of any special tools or equipment.

The invention in its broader aspects is not limited to the specific mechanisms shown and described but departures may be made therefrom

within the scope of the accompanying claims without departing from the principles of the invention and without sacrificing its chief advantages.

What I claim is:—

1. A device for supporting a permanent waving heater cord comprising a member provided with a pair of spaced apart axially aligned apertures through which the heater cord may slide, an annular member to surround said cord and positioned between said apertures, a pin extending radially from said annular member and slidably in said first member, spring means for moving said annular member out of alignment with said apertures to frictionally grip said cord, and a supporting pin extending from said first member by which the device may be supported.

2. A device for supporting a permanent waving heater cord comprising a member provided with a pair of spaced apart, axially aligned apertures through which the cord may slide, a second apertured member to be positioned in alignment with and between said axially aligned apertures, means for resiliently urging said second member out of alignment, and a pin by which said device may be supported.

3. In a permanent waving machine, the combination of supporting and electricity distributing members to be positioned over the customer's head, a set of heater units for permanent waving, each heater unit comprising a detachable connector for attaching a pair of heaters to said member, flexible conductors and a pair of heaters and individual supports through which said conductors may slide and by which said conductors are frictionally held, and means for individually detachably attaching said supports to said supporting member, whereby any heater unit may be quickly detached from said distributing member and replaced by another heater unit.

4. In a permanent waving machine, the combination of a pair of heaters, a separable connector, conductors connecting said heaters to said connector and conductor supporting devices slidably with respect to and frictionally gripping said conductors.

5. A heater unit for permanent waving including in combination a pair of heaters, a separable connector, flexible conductors connecting said heaters to said connector and individual gripping devices for supporting said conductors, slidable with respect to said conductors and gripping their respective conductors in any position.
